Primary Examiner — Clare E Heflin*(74) Attorney, Agent, or Firm* — Leanne Taveggia Farrell; Westman, Champlin & Koehler, P.A.(57) **CLAIM**

The ornamental design for a light, as shown and described.

DESCRIPTION

FIG. 1 is a perspective view of a light;

FIG. 2 is a side view thereof, the opposing side, the front and the rear being identical;

FIG. 3 is a top view thereof; and,

FIG. 4 is a bottom view thereof.

The broken lines shown in the drawings are included for purposes of illustrating portions of the light and form no part of the claimed design.
